UNITED STATES PATENT OFFICE

JOHN G. TSAGARIS, OF WEST MILLCREEK TOWNSHIP, ERIE COUNTY, PENNSYLVANIA,
ASSIGNOR TO ERIE CITY IRON WORKS, OF ERIE, PENNSYLVANIA, A CORPORATION
OF PENNSYLVANIA

FEEDING MECHANISM

Application filed July 16, 1929. Serial No. 378,786.

In feeding material for varying purposes, such as coal to a pulverizer, it is desirable to provide the feeding mechanism with means by which the quantity of material fed may be varied. The present invention is designed to accomplish this purpose and to lock the feeding mechanism in adjustment for various feeds and also to indicate in a simple and convenient manner the adjustment of the feeding mechanism. Other features and details of the invention will appear from the specification and claims.

A preferred embodiment of the invention is illustrated in the accompanying drawings 15 as follows:—

Fig. 1 shows a plan view of the device.

Fig. 2 an elevation, a part being broken away to a section to better show the mechanism.

Fig. 3 a side elevation of the locking finger.

1 marks the frame of the feeder. A discharge opening 2 extends through the frame. The frame is provided with a vertical bearing 3 carrying a shaft 4 which is driven from any convenient source of power (not shown). A feed table 5 is mounted on the upper end of the shaft and is rotated by the shaft. A deflecting finger 5a engages 25 the material on the feed table and deflects the material into the discharge opening. A feed chamber 6 has a surrounding flange 7 which is secured to a surrounding flange 8 on the frame. Arms 9 lead from the walls 30 of the feed chamber to a nut 10 which is preferably concentric with the feed table. A feed tube 11 extends through the nut 10, the tube being preferably provided with screw threads 12 engaging the threads of 35 the nut 10. A hopper 13 is carried by the tube 11 and discharges into this tube.

Handles 14 extend from the upper end of the tube 11 by means of which the tube may be readily screwed downwardly or upwardly to vary the distance between the end of the tube and the rotating table. In this way the quantity of feed may be varied.

In order to lock the tube in adjustment a locking finger 15 is provided. This finger 40 is pivotally mounted on a pin 16, the pin

extending between ears 17 carried by the flange 7. A spring 18 is coiled around the pin 16 and has one end engaging the flange 7 of the chamber 6 and the opposite end the finger 15. This spring 55 yieldingly forces the finger inwardly to its locking position.

The finger is provided with a scale 21 which may be readily read in connection with marks 22 on the ends of the arms 14. Thus the exact adjustment of the tube and 60 the relative feeding opening can be definitely determined from the exterior of the device.

In operation, when it is desired to adjust the feed, the finger 15 is withdrawn and 65 the tube screwed up, or down, by means of the handle 14 and again locked by the finger 15. Preferably the finger is in the shape of a fork which straddles one of the handles 14, but the tendency of the tube is 70 to move only in one direction and in some instances only one side of the fork may be required.

A stirring finger 19 may be secured to the shaft 4. A convenient way of securing this 75 finger is by extending it from a nut 20 screwed on to the upper end of the shaft and securing the turn table 5 on the shaft.

What I claim as new is:—

1. In a feeding mechanism, the combination of a frame; a rotating feeding platform mounted in the frame; a feed tube above the platform; means adjusting the tube toward and from the platform comprising a screw formed on the surface of the tube; and a finger mounted on the frame locking the tube in adjustment. 80

2. In a feeding mechanism, the combination of a frame; a rotating feeding platform mounted in the frame; a feed tube above the platform; means adjusting the tube toward and from the platform; and means locking the tube in adjustment comprising a yielding locking finger and an abutment, one on the tube and the other on 85 the frame. 90

3. In a feeding mechanism, the combination of a frame; a rotating feeding platform mounted in the frame; a feed tube above the platform; means adjusting the 95 tube 100

tube toward and from the platform comprising a screw formed on the surface of the tube; and means locking the tube in adjustment comprising a spring-actuating finger 5 on the frame and an abutment on the tube.

4. In a feeding mechanism, the combination of a frame; a rotating feeding platform mounted in the frame; a feed tube above the 10 platform; means adjusting the tube toward and from the platform comprising a screw formed on the surface of the tube; means locking the tube in adjustment comprising a spring-actuated finger on the frame and an abutment on the tube; and a scale on 15 the finger.

5. In a feeding mechanism, the combination of a frame; a rotating feeding platform mounted in the frame; a feed tube above the platform; means adjusting the 20 tube toward and from the platform comprising a screw formed on the surface of the tube; and means locking the tube in adjustment comprising operating handles extending from the tube and a spring-actuated finger on the frame engaging the 25 handles.

In testimony whereof I have hereunto set my hand.

JOHN G. TSAGARIS.
